UNITED STATES PATENT OFFICE

JAMES W. BRYCE, OF BLOOMFIELD, NEW JERSEY, ASSIGNOR TO THE TABULATING MACHINE COMPANY, OF ENDICOTT, NEW YORK, A CORPORATION OF NEW JERSEY

ALPHABETICAL CODE PUNCHING DEVICE

Application filed March 23, 1925. Serial No. 17,685.

The present invention is directed to an improvement in punching devices for punching tabulating cards.

In the making of these cards for directory work it has become the practice to code the alphabet and utilize multiple punchings to denote letter characters. The punching of such coded multiple punched cards with punching devices now in use requires a considerable amount of skill as ordinarily it is necessary for the operator to perform the coding operation mentally and then to strike the proper combination of keys to accord with the coded character. In other devices utilizing combinational holes for denoting alphabetical characters the machine itself effects the coding but the actual punching operation is effected by the power of the operator's fingers.

The present invention is directed to the provision of a simple punching device which is adapted to be controlled by a keyboard similar to that used on typewriting machines and in which the coding of the characters is effected automatically by the machine and in which the direct labor of punching is performed by the machine itself instead of by the operator as heretofore.

According to the present invention the operator strikes the usual typewriter form of keys. The operation of these keys effects the selection of the desired combinations of punches and thereafter the punching operation itself is performed by the power derived from a translating device in the punching attachment. The operator merely depresses the keys for controlling and selecting purposes and all other operations are performed automatically by the machine. According to the present invention the only effort required upon the part of the operator is the effort required to close a single pair of contacts associated with each key and all the other operations are performed automatically and by an outside source of power.

Further objects and advantages of the present invention will be hereinafter set forth in the accompanying specification and claims and shown in the drawings which by way of

illustration portray one embodiment of my invention.

In the drawings,

Fig. 1 is a top plan view of the complete apparatus.

Fig. 2 is a view of the card punched by the punching device.

Fig. 3 is a sectional view through the keyboard showing the contact devices, the section being taken on line 3-3 of Fig. 1.

Fig. 4 is a sectional view of the punching attachment, the section being taken on line 4-4 of Fig. 1.

Fig. 5 is an enlarged sectional view of certain parts in the punching attachment in moved position.

Fig. 6 is a top plan view of parts of the punching attachment on an enlarged scale.

Fig. 7 is a circuit diagram of the machine.

The machine in general includes a keyboard section designated A and a punching section designated B. The punching section B in its general characteristics is similar to devices already in use. It consists of the usual electric key punch previously utilized for punching the tabulating cards. The particular form herein used is more fully shown and described in the copending application of John T. Schaaff, Serial No. 731,980, filed August 14, 1924. A somewhat similar form of punching device is shown in the patent of L. C. Reynolds No. 1,298,400. The punching attachment includes the usual mechanism for feeding the cards through the machine. The principle of operation utilized with punches of this character is to provide a plurality of punches 20 disposed across the punching attachment, each punch corresponding to a particular index point perforation in the card. In the present embodiment twelve such punches are provided. In the operation of the punching attachment a punching operation is effected upon one column of the card, then the card is displaced relatively to the punches and a second punching operation is performed in another column on the card. The arrangement of the parts is such that feed of the card takes place after each punching operation. The card feed is usually effected by means of a spring 100

such as is shown in the Reynolds patent and the feeding action is controlled after each punching operation by suitable escapement mechanism well known in the art.

5 Within the punching section B there are a plurality of selecting magnets 21, one selecting magnet being provided for each punch. These selecting magnets, when energized, effect the selection of the punches in the following manner.

10 Referring to Figs. 4 and 5 a selecting magnet 21, when energized, attracts its armature 22 thus depressing a plunger 23 and through bell crank 24 thrusts forward an interposer bar 25 over its corresponding punch 20. The forward movement of any interposer bar is adapted to impart a rocking movement to a bail 26, which bail is suitably connected to a link 27 which extends rearwardly and actuates contacts 28 to close the same. The closure of these contacts establishes a circuit to the main punch actuating magnet 29. This magnet being energized rocks a bail 30 downwardly. Bail 30 is disposed over the interposer bars and the downward movement of this bail will depress any interposer bar or bars which have previously been thrust forward by their corresponding selector magnets and in this way depress the corresponding punches 20 through the card. Other punches correlated to interposer bars which are not thrust forward are not actuated by bail 30 inasmuch as their interposer bars will be in the position shown in Fig. 5. The bars 20 when in this position will present a clearance notch 31 under the bail 30 and permit the depression of the bail without the depression of the corresponding interposer bars. The movement of the bail 30 is also utilized 15 to reopen contacts 28 previously closed by the drawing forward of link 27. For this purpose link 27 is made hook-shaped and is hooked over bail 26. The bail 30 has a bracket portion 33 carried thereby which extends under a projecting foot on link 27. (See Fig. 6.) Upon the elevation of part 33 link 27 is released from bail 26 and is drawn backwardly by means of its spring to permit reopening of contacts 28.

20 Also disposed in the punching section of the machine there is a magnet 21a which is energized when a spacing operation is to be effected without the effecting of punching. This magnet 21a has the usual interposer bar 25 associated therewith but there is no punch disposed cooperating therewith.

25 Referring now to the keyboard section of the machine, this section comprises a frame 35 similar to that of a typewriter. Suitably pivoted in the frame are keys 36 similar to typewriter keys. Each key 36 has connected to it a pull rod 37 connected to a bell crank 38 provided with an insulated roller 39. The depression of any key is adapted to close pairs of contacts 40, 41, which are disposed directly

above the insulating roller 39. Each contact combination 40, 41, is made up of a lower blade 43, an intermediate blade 44 and an upper blade 45. In the operation, closing of contacts 41 is followed by closing of contacts 40. Referring now to the circuit diagram (Fig. 7) each upper blade 45 is connected to common line 46. Each intermediate blade 44 is connected by a suitable wire to a bus bar 47. Each lower blade 43 is connected to a corresponding bus bar 47a. Bus bars 47 and 47a of which there are a pair for each key and contact combination extend transversely across a series of conductor bars 48 which are individually connected in series to the selector magnets 21. There is accordingly one bar 48 for each selector magnet 21. Bars 47 and 47a are provided with threaded apertures 49 over each bar 48. In these apertures suitable screws 50 can be placed depending upon the particular combination or coding which it is desired to establish.

30 Referring to the contact combination marked T, for example, it is noted that there are two screws 50 in position. Therefore 35 upon the closing of the contact combination by the T typewriter key the lower connecting bar and the fourth connecting bar from the top are energized. Thus two selector magnets 21 will be energized concurrently 40 and two punches will be called into operation to punch on the card a nine hole marked 52 and a one hole marked 51. This will effect the proper coded punching for the punching of the symbol T.

35 It will be understood that the current flows from source 53 through wire 46, through the selected contacts 40, 41, thence through cross bars 48, magnets 21, and back through wire 54 to source. The main punch operating 40 magnet circuit 55 is closed through contacts 28 as previously explained thus bringing about the simultaneous actuation of one or more punches. The cross transposer bars 47, 47a, 48, provide a simple arrangement for 45 changing the coded combinations without re-wiring the machine. It will be understood that the typewriter may be provided with the usual space key or special key 56 for effecting spacing, which key can be arranged to close a pair of the contacts to the space magnet 21a. Such space key circuit it will be understood is in no wise related to the selector magnet circuit but is an independent circuit shown at 57 and extending through contacts 58 50 which are closed upon the depression of the space key.

45 What I claim is:—

1. In an apparatus of the class described, the combination of a series of keys, a series 55 of punches, a set of bus bars, a plurality of which are connected in pairs with each of a few of said keys, and means comprising another set of bus bars intersecting the first mentioned set of bars and connected to said 60

punches so that different desired combinations of punches may be placed under control of any of the keys.

2. In an apparatus of the character described, the combination of a series of keys, of a plurality of bus bars for each key, a contact for each of the bus bars, said contacts being closed by operations of the associated keys, a plurality of punches, a magnet 10 controlling each of the punches, and means whereby any desired magnet may be connected to any desired bus bar.

3. In an apparatus of the class described, the combination of a series of keys, a series 15 of punches to be operated in code combinations upon operation of the keys, a plurality of bus bars for each of the keys, a bus bar for each of the punches, and means whereby any one of the key bus bars may be connected 20 to any one of the punch bus bars to set up the different combinations of punches to be called into play by selective operation of the keys.

4. In an apparatus of the class described, 25 the combination of a series of keys, a plurality of contacts operated by each of said keys, a series of punches to be brought into operation by the operation of said contacts, and means comprising intersecting bus bars 30 coordinated with said punches and contacts for bringing different combinations of punches under the control of any of the keys.

5. In a punching machine, a plurality of punches, a plurality of connections for effecting actuation of said punches, a plurality of contacts, a key for operating said contacts, and means for associating selected combinations of said connections with said contacts to effect actuation of corresponding combinations 35 of several punches, said means being shiftable relative to said connections to vary the combination of connections associated with said key whereby the same movements of said key may be made to select different 40 punch combinations.

In testimony whereof I hereto affix my signature.

JAMES W. BRYCE.
